UNITED STATES PATENT OFFICE.

DUGALD H. ROBERTS, OF DETROIT, MICHIGAN.

DESIGN FOR A LUBRICATOR-BODY.

SPECIFICATION forming part of Design No. 28,654, dated May 17, 1898.

Application filed June 30, 1897. Serial No. 643,030. Term of patent 14 years.

To all whom it may concern:

Be it known that I, DUGALD H. ROBERTS, a citizen of the United States, residing at Detroit, in the county of Wayne, State of Michigan, have invented and produced a new and original Design for a Lubricator-Body, of which the following is a specification, reference being had to the accompanying drawings, and to the letters of reference marked thereon, which form a part of this specification.

This invention relates to a design for a lubricator-body.

My design consists, essentially, in the general contour and configuration of the body of a lubricator, as shown in the accompanying drawings, in which—

Figure 1 is a side elevation of the design. Fig. 2 is a transverse section on line 2 2 of Fig. 1.

In my design, A designates a globular body having depending therefrom the transverse member B, provided at opposite ends with the right-angled members D and H, respectively.

Projecting from the rounded body A, near its upper end, is a T-shaped member C, having at its outer end an upwardly-projecting member E, the whole presenting a design for the body of a lubricator of original and peculiar shape.

Having thus fully set forth my invention, what I claim is—

The design for a lubricator-body substantially as shown and described.

In testimony whereof I affix my signature in presence of two witnesses.

DUGALD H. ROBERTS.

Witnesses:

E. S. WHEELER,
M. A. MARTIN.
